UNITED STATES PATENT OFFICE.

CLARENCE M. McCLURE, OF DETROIT, MICHIGAN, ASSIGNOR TO FREDERICK STEARNS & CO., OF DETROIT, MICHIGAN, A CORPORATION OF MICHIGAN.

DESIGN FOR A BOTTLE.

50,395.

Specification for Design.

Patented Feb. 27, 1917.

Application filed August 21, 1916. Serial No. 116,209. Term of patent 14 years.

To all whom it may concern:

Be it known that I, CLARENCE M. McCLURE, a citizen of the United States of America, residing at Detroit, in the county of Wayne and State of Michigan, have invented a certain new, original, and ornamental Design for a Bottle, of which the following as a specification, reference being had therein to the accompanying drawings forming part thereof, in which—

I claim:

The ornamental design for a bottle, substantially as shown.

CLARENCE M. McCLURE.
